[57] **CLAIM**

The ornamental design for a sewerless toilet or similar article, substantially as shown and described.

DESCRIPTION

FIG. 1 is a right side elevational view of a sewerless toilet embodying our new design, the left side being a mirror image of the right side shown;

FIG. 2 is a front elevational view thereof;

FIG. 3 is a top plan view thereof;

FIG. 4 is a rear elevational view thereof;

FIG. 5 is a bottom plan view thereof, and

FIG. 6 is a perspective view taken from the top, front and right side of a modified form to the sewerless toilet shown in FIG. 1.

FIG. 1

FIG. 2

FIG. 3
